AU 291

EX

OR D 11,526

Design No. **11,526**, dated November 25, 1879

UNITED STATES PATENT OFFICE.

ELI H. ELDRIDGE AND JOHN H. ELDRIDGE, OF TAUNTON, MASSACHUSETTS.

DESIGN FOR COFFIN-PLATES.

Specification forming part of Design No. **11,526**, dated November 25, 1879; application filed October 18, 1879.
[Term of patent 3½ years.]

To all whom it may concern:

Be it known that we, ELI H. ELDRIDGE and JOHN H. ELDRIDGE, both of Taunton, Bristol county, Massachusetts, have invented a certain new and Improved Design for Coffin-Plates; and we do hereby declare the following to be a full, clear, and exact description of the same, reference being had to the accompanying illustration, which represents a front view of the said design.

Our invention has for its object to provide an ornamental name-plate for coffins, which shall be neat in appearance and carry upon its face a symbolic representation of the event which it is intended to record.

To this end our invention consists of a plate, of any suitable material, having upon its face the representation of a bound sheaf of ripe grain with a sickle secured therein, as shown.

The shape of the plate is preferably rectan-

gular, though other shapes may be employed, this not being an essential feature of the invention, and the edge of the plate may be ornamented in any desired manner, if preferred.

The representation of the sheaf of grain and the sickle are preferably arranged at one end of the plate when the latter is made rectangular, as shown, in order that sufficient room be left for the inscription.

We claim as our invention—

The design for coffin-plates herein described, consisting of the plate surmounted with the symbolic representation of a sheaf of ripe grain and a sickle, as set forth.

ELI H. ELDRIDGE.
JOHN H. ELDRIDGE.
